UNITED STATES PATENT OFFICE.

ERNST HUSCHKE, OF SAALFELD, GERMANY.

SHUTTLE-OPERATING MECHANISM FOR POWER-LOOMS.

SPECIFICATION forming part of Letters Patent No. 593,941, dated November 16, 1897.

Application filed July 23, 1896. Serial No. 600,261. (No model.) Patented in Germany June 9, 1895, No. 85,292.

To all whom it may concern:

Be it known that I, ERNST HUSCHKE, a subject of the Duke of Saxe-Meiningen, and a resident of Saalfeld, Germany, have invented 5 certain new and useful Improvements in Shuttle-Operative Mechanism for Power-Looms, (for which I have obtained a patent in Germany, No. 85,292, dated June 9, 1895,) of which the following is a full, clear, and exact specification, reference being had to the accompanying drawings, wherein—

Figure 1 is a front elevation, and Fig. 2 a side view, of a loom with my improved mechanism, showing its position when the batten is started from its lowest position and the shuttle-operating mechanism on the right-hand side of the loom unloaded. Fig. 3 is an elevation, Fig. 4 a side view, and Fig. 5 a detailed top view, of a part of a loom, showing my 15 improved shuttle-operating mechanism in action when the batten is moved upward. Fig. 6 is an enlarged detail, a side view of the shuttle-operating mechanism set in position, attained when the batten reaches its highest 20 position. Fig. 7 is a sectional view on line 77 in Fig. 6. Fig. 8 is a similar view as Fig. 6, showing the shuttle-operating mechanism after discharging the shuttle. Fig. 9 is a section on line 99 in Fig. 8.

Similar letters of reference indicate corresponding parts in all the views of the drawings.

My invention relates to power-loom; and it consists of the hereinafter-described mechanism for operating the shuttle, comprising devices for setting springs actuating the shuttle on both sides of the loom simultaneously when the batten moves upward and releasing them alternately when it returns.

The mechanism is particularly applicable to power-loom having perpendicularly-moving batten, the striking-bolts, pressed against by the springs, being driven outward against the pressure of the springs while the batten 45 is moved upward, then arrested by ratchet-bars, holding the springs set, and then released alternately by mechanism operated independently of the batten from the driven shaft. The shuttle moves on the reed and the driving mechanism is attached to the batten.

The frame of the loom shown in Fig. 1 is composed of the two standards *a* and their

connecting-ties. The batten *b* is shown in its lowest position.

A is the main driving-shaft, and *d*² disks set 55 thereon and driving, through crank-pins *d*' and connecting- rods *d*, batten *b* on slide-ways *c*.

Springs *k*⁴ are flat and made of tempered steel. Their lower ends are screwed to brackets *l* *l*', secured to the batten *b* and projecting downward at a right angle to it.

Bolts *k* slide in sleeves *k*', secured to the batten. They are made, preferably, round and provided with a spline *sp*. Sleeves *k*' are 65 provided with a corresponding groove, wherein spline *sp* engages to keep the bolts *k* from turning. The heads of the bolts *k* are forked and rollers *k*³ are set on pins *z*, pillowied 70 therein, to relieve friction between the bolts and the springs *k*⁴. Upon the same pins *z* are set rollers *i*, running upon rails *h*' of the setting-brackets.

Brackets *h*, forming sloping rails *h*', are attached on the outside of the standards *a* of the frame, as shown in Fig. 5 in detail. Rollers *i* engage against the sloping rails *h*' when the batten *b* is moved upward, and as the batten *b* moves upward bolts *k* are drawn outwardly until ratchet-bars *n* slide into corresponding recesses *rc*, (shown in Fig. 7,) provided in the bolts *k*, arresting them in their extended position. This part of the mechanism is illustrated in detail in Figs. 6, 7, 8, and 9. Ratchet-bars *n* are pivoted on bolts *n*⁴, 85 set in bars *s*, and springs *n*³, attached to their outer ends, draw them downward. The other ends of the ratchet-bars *n*, projecting beyond the bolts *n*⁴, are connected by links *r*' and *r*² to brackets *r*³, screwed to the bottom of the 90 shuttle-way.

The releasing of the bolts *k* for the purpose of imparting motion to the shuttle is accomplished by mechanism operated from the driving-shaft and lifting alternately the ratchet-bars on each side of the loom. This mechanism is arranged as follows:

To the shaft *t*, driven from the main driving-shaft *A* by cog-wheels *g*³ and *g*⁴, is keyed cam *o*³, having two diametrically opposite sections *o*⁴ and *o*⁵. Rocking rod *o*', pivoted to bracket *o*², engages with its forked lower end *o*⁷ the cam *o*³ and imparts the rocking motion produced thereby to the horizontal bar *o*. On

each end of the bar is a block o^6 , and as the bar o is moved to and fro these blocks strike alternately against the ratchet-bars n , while the batten moves downward, thereby lifting them and releasing the bolts, which, driven by the rebounding action of the springs, impart a forcible motion to the shuttle.

I claim as my invention and desire to secure by Letters Patent—

- 10 In mechanism for imparting motion to the shuttle of a power-loom, the combination of a batten, sleeves, having keyways, secured to the ends of the shuttle-way; striking-bolts, having forked heads, sliding in the sleeves; 15 splines set in the bolts; pins or spindles set crosswise in the forked heads of the striking-bolts and projecting to one side therefrom, antifriction-rollers set on these pins or spindles between the tines of the forked heads; 20 downward-extending brackets secured to the batten, one on each end; springs, secured to the ends of the brackets and engaging these rollers; antifriction-rollers set on the projecting ends of the pins or spindles; sloping rails,

secured to the standards of the loom-frame in 25 position to engage these outer rollers, ratchet-bars, pivoted to the ends of the shuttle-way and adapted to drop into recesses provided in the striking-bolts; springs drawing the ratchet-bars downward; a shaft pillow'd in 30 the standards of the loom-frame above the driving-shaft; a gearing transmitting the motion from the driving-shaft to this shaft; a spiral cam, set on this shaft; a horizontally-disposed sliding bar, vertically upward 35 projecting blocks, set one on each end of the horizontally-disposed sliding bar; a rocking rod, engaging with its forked end the spiral cam, and shifting the sliding bar to and fro, thereby alternately lifting the ratchet-bars and releasing the striking-bolts.

In testimony whereof I have signed this specification in the presence of two subscribing witnesses.

ERNST HUSCHKE.
